UNITED STATES PATENT OFFICE

166,853

COMBINED NOSE AND EYE PROTECTOR

Estel D. Felch, Madison, Wis.

Application February 28, 1952, Serial No. 18,699

Term of patent 14 years

(Cl. D57—1)

To all whom it may concern:

Be it known that I, Estel D. Felch, a citizen of the United States, residing at Madison, in the county of Dane and State of Wisconsin, have invented a new, original, and ornamental Design for a Combined Nose and Eye Protector, of which the following is a specification, reference being had to the accompanying drawing, forming part thereof.

The dominant features of my design reside in the portions shown by full lines.

I claim:

The ornamental design for a combined nose and eye protector, as shown and described.

ESTEL D. FELCH.
